(57) **CLAIM**

The ornamental design for a gas manifold as shown and described.

DESCRIPTION

FIG. 1 is a perspective view of a first embodiment of a gas manifold, showing my new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a cross-sectional view taken along 8-8 of FIG. 6;

FIG. 9 is an exploded perspective view thereof;

FIG. 10 is a perspective view thereof, showing an exemplary nipple fitting adjacent the gas manifold;

FIG. 11 is the cross-sectional view of FIG. 8, showing an exemplary nipple fitting attached to the gas manifold;

FIG. 12 is a perspective view of a second embodiment of a gas manifold, showing my new design;

FIG. 13 is a left side elevation view thereof;

FIG. 14 is a right side elevation view thereof;

FIG. 15 is a front elevation view thereof;

FIG. 16 is a rear elevation view thereof;

FIG. 17 is a top plan view thereof;

FIG. 18 is a bottom plan view thereof;

FIG. 19 is a cross-sectional view taken along 19-19 of FIG. 17;

FIG. 20 is an exploded perspective view thereof;

FIG. 21 is a perspective view thereof, showing an exemplary nipple fitting adjacent the gas manifold;

FIG. 22 is the cross-sectional view of FIG. 19, showing an exemplary nipple fitting attached to the gas manifold;

FIG. 23 is a perspective view of a third embodiment of a gas manifold, showing my new design;

FIG. 24 is a left side elevation view thereof;

FIG. 25 is a right side elevation view thereof;

FIG. 26 is a front elevation view thereof;

FIG. 27 is a rear elevation view thereof;

FIG. 28 is a top plan view thereof;

FIG. 29 is a bottom plan view thereof;

FIG. 30 is a cross-sectional view taken along 30-30 of FIG. 28;

FIG. 31 is an exploded perspective view thereof;

FIG. 32 is a perspective view thereof, showing an exemplary nipple fitting adjacent the gas manifold;

FIG. 33 is the cross-sectional view of FIG. 30, showing an exemplary nipple fitting attached to the gas manifold;

FIG. 34 is a perspective view of a fourth embodiment of a gas manifold, showing my new design;

FIG. 35 is a left side elevation view thereof;

FIG. 36 is a right side elevation view thereof;

FIG. 37 is a front elevation view thereof;

(Continued)

FIG. 38 is a rear elevation view thereof;
 FIG. 39 is a top plan view thereof;
 FIG. 40 is a bottom plan view thereof;
 FIG. 41 is a cross-sectional view taken along 41-41 of FIG. 39;
 FIG. 42 is an exploded perspective view thereof;
 FIG. 43 is a perspective view thereof, showing an exemplary nipple fitting adjacent the gas manifold; and,
 FIG. 44 is the cross-sectional view of FIG. 41, showing an exemplary nipple fitting attached to the gas manifold.
 The broken lines in the figures illustrate portions of the gas manifold that form no part of the claimed design.
